UNITED STATES PATENT OFFICE

92,495

DESIGN FOR A BUILDING

Norman J. Schlossman and John Demuth, Chicago, Ill., assignors to The White Castle System of Eating Houses Corporation, Wichita, Kans., a corporation of Kansas

Application March 15, 1934, Serial No. 51,069

Term of patent 14 years

To all whom it may concern:

Be it known that we, NORMAN J. SCHLOSSMAN and JOHN DEMUTH, citizens of the United States, both residing at Chicago, in the county of Cook and State of Illinois, have invented a new, original, and ornamental Design for a Building, of which the following is a specification, reference being had to the accompanying drawing, forming a part thereof.

Figure 1 is a perspective view of the building embodying the features of this design, lettered

portions thereon being shown in dotted lines to suggest words or names indicative of the function, owner or the like of the building;

Fig. 2 is a side elevational view of Figure 1; and

Fig. 3 is a front elevational view of Figure 1.

We claim:

The ornamental design for a building substantially as shown and described.
